UNITED STATES PATENT OFFICE.

MATTHEW O. TROY, OF LYNN, MASSACHUSETTS, ASSIGNOR TO GENERAL ELECTRIC COMPANY,
A CORPORATION OF NEW YORK.

ELECTRIC CONDENSER.

No. 888,275.

Specification of Letters Patent.

Patented May 19, 1908.

Application filed March 31, 1902, Serial No. 100,717. Renewed November 11, 1907. Serial No. 401,730.

To all whom it may concern:

Be it known that I, MATTHEW O. TROY, a citizen of the United States, residing at Lynn, county of Essex, State of Massachusetts, have invented certain new and useful Improvements in Electric Condensers, of which the following is a specification.

My present invention relates to electrical condensers and is particularly valuable where it is desired to produce a condenser capable of withstanding high electromotive forces without breaking down and without heating unduly.

In making up a condenser in accordance with my invention, I employ a dielectric of composite structure, one of the elements of which possesses a relatively high resistance to break down, and the other a relatively high insulation resistance.

20 The drawing represents a condenser of my invention in process of construction.

The novel features of the invention are pointed out in the appended claims, and the details of construction of a condenser embodying the invention are described in the following specification.

In building up a condenser in accordance with my invention, I make use of a varnished paper as the medium for securing high resistance to break down of the condenser, and associated with the varnished paper are sheets of paper impregnated with paraffin or other wax or mixtures of waxes. Instead of impregnating the sheets of paper with paraffin or other wax before assembling them in the condenser, I prefer to postpone this operation until the condenser has been assembled, after which the condenser as a whole may be treated in a bath of wax as set forth, for example, 30 in the patent to Thomson No. 691,675, January 21, 1902. In the case of the varnished paper employed as a part of the dielectric of the condenser, I prefer to prepare this prior to assembling the condenser.

45 The drawing represents a condenser in process of assembling. The compact bundle of sheets at 1 indicates the portion already assembled, while the separate sheets 2, 3, 4 and

5 indicate the order in which the subsequent sheets are to be superposed. The part 6 represents a sheet of tin-foil upon which is superposed an untreated sheet 2 which may be of bond paper, then a varnished sheet of bond paper 3, then another untreated sheet of bond paper 4, and then the next sheet of tin-foil 55 and so on.

Instead of placing only a single sheet of untreated bond paper between each sheet of tin-foil and the varnished paper, I may of course for additional security make use of a 60 number of sheets, while in the same way instead of a single sheet of varnished paper I may employ a plurality thereof.

After the condenser has been assembled it is impregnated with a suitable insulating 65 medium, as paraffin wax, thereby filling the untreated paper with the insulating wax and excluding any air or bubbles which may remain in the body of the condenser proper.

The use of varnished paper alone as the 70 dielectric medium enables the condenser to stand very high voltages, but is open to the objection that after the condenser has been running for any length of time it is apt to become dangerously hot, and in some cases 75 may actually crack open due to the considerable amount of heating which may result. This may possibly be due to a leakage of current, but whatever the cause may be I have found that the objection spoken of may be 80 remedied by the employment of the paraffined paper in connection with the varnished paper.

What I claim as new and desire to secure by Letters Patent of the United States, is,— 85

1. An electric condenser built up of sheets of conducting material separated by juxtaposed sheets of paper, one sheet of paper being varnished and the other sheet coated or impregnated with wax. 90

2. An electric condenser built up of sheets of conducting material separated by juxtaposed sheets of paper, one sheet of paper being varnished and the other sheet coated or impregnated with paraffin. 95

3. An electric condenser built up of sheets

of conducting material separated by juxtaposed sheets of paper, one sheet of paper being coated with a material having relatively high resistance to puncture or break down, and the other sheet coated or impregnated with a material having a higher insulation resistance than the first mentioned material.

In witness whereof, I have hereunto set my hand this 28th day of March, 1902.

MATTHEW O. TROY
